JOSEPH PANIK AND STEVE CLEBO, OF WEST PARK, OHIO.

CHURN-OPERATING MECHANISM.

1,398,112.

Specification of Letters Patent. Patented Nov. 22, 1921.

Application filed May 16, 1921. Serial No. 470,174.

To all whom it may concern:

Be it known that we, (1) JOSEPH PANIK and (2) STEVE CLEBO, citizens of Czechoslovakia, residing at West Park, in the county 5 of Cuyahoga and State of Ohio, have invented certain new and useful Improvements in Churn-Operating Mechanisms, of which the following is a specification.

This invention relates to certain new and 10 useful improvements in churn operating mechanisms, the primary object of the invention being to utilize in a novel and practical manner the rocking motion of a rocking chair for actuating the reciprocating 15 flange or stirrer of a churn.

Another object of the invention is to provide incased churn operating mechanism wherein the casing embodies supporting means within the same for the receptacle of 20 the churn, a suitable floor plate being attached to one side of the casing that is formed so as to provide a foot rest, and said floor plate being provided with cogs adapted for engagement with pockets in the 25 rockers of a rocking chair so that when the latter is rocked backwardly and forwardly and operatively connected to the incased churn operating mechanism, the rocking chair is prevented from sliding away from 30 the casing and the operation of the churn thereby insured.

A still further object of the invention is to generally simplify and improve devices of the present character.

With the above general objects in view and others that will appear as the nature of the invention is better understood, the same consists of the novel form, combination and arrangement of parts hereinafter more fully 35 described, shown in the accompanying drawing and claimed.

In the drawing, wherein like reference characters designate corresponding parts throughout the several views,

Figure 1 is a view partly in longitudinal vertical section and partly in side elevation of a churn and operating mechanism constructed in accordance with the present invention,

Fig. 2 is a view partly in plan and partly in section along line II—II of Fig. 1 with the chair removed,

Fig. 3 is a fragmentary elevational view showing the cross head and attached piston and connecting rods.

Fig. 4 is a fragmentary sectional view

showing the operative connection between the rocking chair and the horizontal push rod and taken on line IV—IV of Fig. 5,

Fig. 5 is a rear elevational view of the 60 device shown in Fig. 4.

Referring more in detail to the several views, 1 represents a casing preferably cast in two hollow sections with the lower section open at the top and closed by means of a 65 cap or upper section 16 which may be provided with abutting flanges suitably secured together, the lower section being provided with a transverse bottom member 19 with a circular flange 19' thereon providing a 70 socket in which the churn receptacle 2 is seated, introduction of and removal of the churn receptacle being permitted by leaving the rear of the casing 1 open for a distance 75 at the front as at 35. On the sides of the 75 lower section of the casing 1 are formed aligned pairs of guide ribs 27 between which the opposite ends of a cross head 5 project whereby said cross head is guided for vertical movements, the ends of the cross head 80 5 being arranged as at 28 to prevent undue friction or jamming of the cross head when moving between said guide ribs 27, and the upper end of a piston rod 4 being rigidly attached to the central portion of the cross 85 head 5. The piston rod 4 extends downwardly where it is slidably mounted on the top of the churn receptacle 2 and is attached to the plunger or stirrer 3 of said churn, which stirrer may be of any desired specific 90 construction.

A pair of ears 5' are formed on the upper side of the cross head 5 as shown in Fig. 3, and a pitman or connecting rod 8 has the lower end of the same pivoted to said ears, 95 the upper end of said pitman 8 being pivoted to the crank portion 10' of a crank shaft 10 which has its opposite ends journaled in opposite sides of the casing 1 by the provision of bearings as at 30, which bearings are preferably formed in half sections respectively provided on the upper and lower sections of the casing at the joint between said sections. A pocket gear wheel 11 is secured upon the crank shaft 10 at one side of the crank portion 10' thereof, and the same meshes with 100 a spur gear 12 which is fixed upon a transverse horizontal shaft 29 which is journaled rearwardly of the shaft 10 within the casing 1 in bearings 36 on the sides of said casing 110 1 which are similar to the bearings 30. Another spur gear 13 is fastened upon the shaft

29 and the same meshes with a segment gear 14 disposed therebeneath and pivoted as at 15 to the casing substantially directly beneath the shaft 29, an arm 14' being formed 5 integral with the hub of the segment gear 14 and projecting downwardly from the pivot 15 where it is connected slidably and pivotally by means of a pin and slot connection 18 to the forward end of a push 10 rod 17 which is arranged near the bottom of the casing and which is slidably disposed through the rear wall of said casing as at 17'. The rear wall of the casing 1 is inwardly offset near the bottom of the same 15 as at 37 and is then provided with a rearward extension as at 38 which forms a foot rest for a person occupying the rocking chair 24 as will presently become apparent, the foot rest 38 being arranged to overlie a portion 20 of the rod 17.

A floor plate composed of an open rectangular frame 21 is disposed rearwardly of the casing 1 and has a flange 21' at its forward end suitably fastened to the casing 1 25 at the rear of the foot rest 38, the side bars of the frame 21 being provided with upwardly projecting teeth 25 which engage in suitable pockets 25', provided in the rockers of the chair 24.

30 The push rod 17 extends rearwardly and terminates at the rear of the chair 24 where it is connected to the lower end of a lever 39 by a pin and slot connection 40, the lever 39 being centrally pivoted upon a horizontal 35 axis as at 41 between and to the upper ends of a pair of arms 20 which are integrally connected to the side bars of the frame 21. The upper end of the lever 39 is pivoted as at 22 to a bracket 23 which is rigidly fastened to the back of the chair 24, and a spring 26 is fastened to the push rod 17 and bears upon the lever 39 so as to yieldingly resist relative movement of these parts.

In operation, the parts are disposed as 45 shown in Fig. 1 so that a person occupying the chair 24 may rest his or her feet upon the foot rest 38 and manually cause rocking of the chair in the well known manner. The engagement of the teeth 25 with the 50 rockers prevent relative separation of the casing 1 and the rocking chair so that rocking of said chair positively causes longitudinal reciprocation of the push rod 17 through rocking of the lever 39. Sliding movement 55 of the push rod 17 oscillates the segment gear 14 and this imparts oscillatory rotary motion to the gears 13, 12 and 11 and also to the crank 10'. The pitman 8 and piston rod 4 are accordingly reciprocated for causing 60 the stirrer 3 to reciprocate within the receptacle 2 for churning material therein.

When the churning operation has been completed, the crank 10 may be moved to a vertical position so that the stirrer 3 and rod 4 are withdrawn from the body of the receptacle 2 along with the cover of the latter. The body of the receptacle 2 may then be removed through the opening 35 and after the same is emptied it may be replaced or a new one may be substituted for repeating 70 the operation.

By forming the bearings 30 and 36 in half sections at the adjacent edges of the sections of the casing 1, the parts may be quickly originally assembled or removed for 75 renewal or repair with considerable ease. The present construction accordingly provides a simplified and durable mechanism for the operation of churn-dashers or equivalent reciprocated members and provides for 80 incasing the gears and other movable parts so that the device will have a neat appearance and so that catching of the person's clothing in moving parts is rendered unlikely.

It is believed that the construction and operation as well as the advantages of the present invention will be readily understood and appreciated by those skilled in the art.

Minor changes may be made in the invention without departing from the spirit and scope thereof.

What is claimed as new is:—

In a churn operating mechanism, of a receptacle, a member to be actuated disposed 95 within the receptacle, guide strips upon the inner side walls of the receptacle, a crank shaft journaled within the receptacle and adjacent the upper ends of the guide strips, a gear wheel keyed to said crank shaft, a 100 segment gear pivotally mounted within the receptacle, connections between the segment gear, crank shaft gear and means externally of the receptacle for actuating said segment gear, comprising an open substantially rectangular frame rigidly attached to the receptacle, a member positioned for rocking movement upon the frame, vertical brackets centrally of the frame and adjacent one end thereof, a lever pivoted intermediate 110 its ends to the upper ends of said brackets, said lever being pivotally mounted upon the said rocking member and a reciprocating shaft between the lower end of said segment gear and the said lever for purposes specified. 115

In testimony whereof we affix our signatures in presence of two witnesses.

JOSEPH PANIK.
STEVE CLEBO.
